UNITED STATES PATENT OFFICE.

AUGUST WIEDENFELD, OF BOCHUM, GERMANY.

MAGNETIC LOCK FOR MINERS' SAFETY-LAMPS.

SPECIFICATION forming part of Letters Patent No. 749,123, dated January 5, 1904.

Application filed January 30, 1903. Serial No. 141,166. (No model.)

To all whom it may concern:

Be it known that I, AUGUST WIEDENFELD, a citizen of the German Empire, and a resident of Bochum, Westphalia, Germany, have 5 invented certain new and useful Improvements in Magnetic Locks for Miners' Safety-Lamps, of which the following is a specification.

My invention relates to improvements in 10 locks of miners' safety-lamps; and its object is the prevention of an unauthorized opening of such lamps. I attain this object by providing in the lock of the lamp a certain distribution of the volume of the bolt at both 15 sides of its swinging center involving a concentration of the inertial energies uniting to a central power in a support below the center of said bolt, so that a stroke against the lamp will merely result in an equable resistance of the bolt owing to the equable distribution of its volume. Besides, my lock is so 20 constructed in contrast with the bolts bearing round a pivot or axis that the bolt cannot turn round nor disjoin. Another advantage is the lateral insertion of the locking device in the magnetic lamp-lock, which permits access to and a removal of the bolt only 25 when the lamp is open. The unlocking of the lamp is done by indirect magnetization 30 of the bolt from an iron core fastly inserted in a brazen screw-ring.

My invention is illustrated by the drawings herewith.

Figure 1 is a view of a lamp vessel, the portion of the latter which is covered by my invention being pointed out in dotted lines. Fig. 2 is a ground plan of the vessel. Figs. 3 and 4 illustrate two different ways of arranging the bolt and two forms in which my 40 invention may be carried out.

The bolt *a* of the lock is provided with a tooth *b* and is placed in a cavity *d* in the side of the vessel, in a brass screw-ring. A spring *f* keeps the said bolt *a* in the position illustrated in Fig. 1. Within the above-mentioned brazen screw-ring *g* there is lodged an iron core *e*. On approaching the latter with a magnet in the direction indicated on the drawings by an arrow it will attract the bolt 45 and will by the flexibility of the spring *f* cause the end of the bolt, which is provided with the teeth *b*, to precede and disengage

from the notch above. To close the lamp, all that is required is to turn the screw-ring *g* down, whereupon the teeth *b* will catch in 55 a suitable notch, the opening being done, as described, by magnetization of the iron core. In the example illustrated by Fig. 1 the aforesaid bolt may be removed when the lamp is open, so that the spring can be looked 60 after and the lock kept in proper order.

In the examples illustrated by Figs. 3 and 4 the iron core *e* and the bolt *a* are both inserted in the screw-ring *g*. This arrangement offers the advantage that it permits, by 65 means of several notches *m* in the vessel, a screwing on or turning tighter of the screw-ring when the thread of the latter wears out by continuous use of the lamp. In order to prevent a dropping out of the bolt when the 70 lamp is being opened, a hole is provided in the bolt, catching a pivot *h*, screwed into the ring. When the lamp is closed, the bolt is not supported, however, by the pivot, the latter on account of the larger size of the hole *h* exercising no effect whatever on the bolt except 75 that it catches the bolt, and thus prevents its dropping out when the lamp is being opened.

Fig. 4 shows an example where the blade-spring *f* is substituted by a spiral spring *l*, 80 catching into a recess in the bolt and keeping it locked. The effect is the same as with the other arrangements above described. A plate *i*, soldered to at the top, covers the bolt *a*. The bottom *k* is provided with a perforation to admit the tooth *b* of the bolt.

What I claim as my invention, and desire to protect by Letters Patent, is—

1. In magnetic locks for miners' safety-lamps, the combination with the casing of 90 the lamp, of a bolt swinging on a point below the horizontal center and substantially at mid-length whereby the volume of the bolt is distributed in substantially equal parts on both sides of said swinging point, substantially as described.

2. In magnetic locks for miners' safety-lamps, the combination of a spring-pressed bolt, of a brass screw-ring provided with a perforation in which is seated an iron core 100 above one end of the bolt, the other end of the bolt being adapted to engage in a notch in said ring.

3. In magnetic locks for miners' safety-

lamps, the combination with the lamp vessel, of a brass screw - ring fitted therein, a bolt swinging about its center in a recess in said brass ring and provided with a tooth at 5 one end, and an iron core fitted in said brass ring, the lamp-casing being provided with a series of notches to receive the bolt-tooth, substantially as described.

In testimony whereof I have hereunto subscribed my name in the presence of two witnesses.

AUGUST WIEDENFELD.
